UNITED STATES PATENT OFFICE.

JOSEPH J. RILEY, OF SAN DIEGO, CALIFORNIA, ASSIGNOR OF ONE-HALF TO WILLIAM R. BYARS, OF SAN DIEGO, CALIFORNIA.

STEAM-GENERATING ATTACHMENT FOR INTERNAL-COMBUSTION ENGINES.

1,205,483.

Specification of Letters Patent. Patented Nov. 21, 1916.

Application filed October 7, 1915. Serial No. 54,525.

To all whom it may concern:

Be it known that I, JOSEPH J. RILEY, a citizen of the United States, residing at San Diego, in the county of San Diego and State 5 of California, have invented certain new and useful Improvements in Steam-Generating Attachments for Internal-Combustion Engines, of which the following is a specification.

10 This invention relates to a steam generating attachment for internal combustion engines, and it embodies an improvement upon the structure shown in my copending application Serial No. 28,650, filed on May 17,

15 1915.

In the application aforesaid I have indicated a steam generating casing clamped upon the exhaust pipe of an internal combustion engine in such manner that the heated exhaust gases will generate steam within said casing which steam is conducted to the intake manifold of the engine. The device shown in the present application is designed to serve the same purpose but in this case, 20 the steam generator casing is cast as an integral unit with the exhaust pipe, the exhaust pipe passing therethrough in such manner as to be entirely surrounded by the water within the casing so that only one 25 thickness of metal is present between the water and the hot exhaust gases and the resultant generation of steam is more rapid and efficient.

The purpose of thus generating steam by 30 utilizing heat derived from the exhaust pipe of an internal combustion engine is to render it possible to supply this steam to the intake manifold of the engine during the time that the engine is running, it being 35 well known that water vapor injected into the carbureted air promotes combustion and aids in preventing the formation of carbon.

It is a further object of the invention to 40 provide a structure of the type just described constructed in such manner that the parts may be very easily and quickly assembled and the whole may be produced at a very small cost.

Further objects and advantages of the invention will be set forth in the detailed description which now follows.

In the accompanying drawing, Figure 1 is a perspective view of a steam generator

casing constructed in accordance with the invention, and Fig. 2 is a longitudinal vertical section therethrough.

Like numerals designate corresponding parts in both of the figures of the drawing.

Referring to the drawing the numeral 5 designates the exhaust pipe of an internal 60 combustion engine. Cast integral therewith is a shell 6 comprising the generator proper. Located within the shell is a float 7 that is carried by a stem 8, said stem being pivoted to an ear 9 of a closure plate 10. The height 65 of the water in the casing is normally maintained at about the line 11 by the float; said float carrying a valve 12 adapted to close the mouth 13, of a water supply pipe 14.

A coil 15 corresponding to the coil shown 70 in my aforesaid application, Serial No. 28,650, has its convolutions disposed beneath the water line, while its terminal end is disposed above the water line at 17.

The general combination herein described 75 is disclosed and claimed in my copending application aforesaid, the present application being intended to cover the type of generator herein described in which the generator is made as an integral unit with the 80 exhaust pipe whereby the more efficient action set forth, as well as a reduction in cost, will be achieved.

It will be seen that all of the parts except 85 the casing and the exhaust pipe are carried by closure plate 10 so that the securing of this plate into position by screws 18 will not only close the casing, but will also secure the float, coil and valve 12 in place.

While the elements shown and described 90 are well adapted to serve the purposes for which they are intended, it is to be understood that the invention is not limited to the precise construction set forth, but includes within its purview such changes as 95 may be made within the scope of the appended claims.

Having described my invention what I claim is:

1. The combination with a steam generator casing, of an exhaust pipe passing therethrough, and lying in spaced relation to the bottom and sides thereof, and made in one piece with said casing, said casing having an opening formed therein and a closure 100 plate for said opening, a float pivoted to said

plate, a valve actuated by said float and a water supply pipe closed by said valve and passing through said plate.

2. The combination with a steam generator casing, of an exhaust pipe passing therethrough, and lying in spaced relation to the bottom and sides thereof, and made in one piece with said casing, said casing having an opening formed therein and a closure plate for said opening, a float pivotally supported by said plate and bodily removable therewith, a valve actuated by said float, a

water supply pipe closed by said valve and passing through said plate and a coil supported from said plate and having a terminal end disposed above the water line within the casing.

In testimony whereof I affix my signature in presence of two witnesses.

JOSEPH J. RILEY.
